UNITED STATES PATENT OFFICE.

ALBERT BROADMEYER, OF HARRISBURG, PENNSYLVANIA, ASSIGNOR TO THE W. O. HICKOK MANUFACTURING COMPANY, OF HARRISBURG, PENNSYLVANIA, A CORPORATION OF PENNSYLVANIA.

PAPER-FEEDING APPARATUS.

Application filed September 8, 1921. Serial No. 499,333.

To all whom it may concern:

Be it known that I, ALBERT BROADMEYER, a citizen of the United States, residing at Harrisburg, in the county of Dauphin and 5 State of Pennsylvania, have invented certain new and useful Improvements in Paper-Feeding Apparatus, of which the following is a specification.

The present invention relates more particularly to means for loosening and elevating the upper sheets of the pile, and the object is to provide simple means, whereby the air blasts employed for this purpose can be regulated to the conditions and the character of the work.

In the accompanying drawings:

Figure 1 is a side elevation of a well-known type of feeding machine showing the improvements in place thereon,

20 Figure 2 is a rear elevation of the same, Figure 3 is a top plan view,

Figure 4 is a view in elevation on an enlarged scale of the controlling valve,

25 Figure 5 is a sectional view therethrough on the line 5—5 of Figure 4,

Figure 6 is a sectional view on the line 6—6 of Figure 5.

In the embodiment disclosed, a suitable frame 7 is employed, in which is mounted 30 a vertically movable table 8 adapted to carry the pile of sheets to be fed. The initial feeding means is in the form of a rotatable suction drum or head 9, and the uppermost sheet of the pile placed on the table 8, is adapted to be loosened, and the topmost sheet 35 brought into contact with the drum 9 by an air blast delivered through twin nozzles 10 adjustably mounted on a supporting rod 11 on the rear side of the frame. To eliminate cohesion other nozzles 12 and 13 are 40 adjustably mounted on above opposite sides of the table.

45 Mounted on the rear portion of the frame is a valve casing 14 having a depending intake nipple 15, an upstanding outlet nipple 16 and two oppositely disposed side outlet nipples 17 and 18. A suitable fan, indicated at 19 and preferably having its intake 20 suitably coupled to the feeding head 9, has 50 an outlet 21 connected by a supply conduit 22 to the intake nipple 15 of the valve casing 14. The upstanding outlet nipple 16 has a branch pipe 23 connected to the nozzles 10.

The nipple 17 is connected by a branch pipe 24 to the nozzle 12, while the nipple 18 is 55 connected by a branch conduit 25 with the nozzle 13.

The central portion of the valve casing 14 has a cylindrical valve chamber 26 that contains a rotary valve head 27 provided with a 60 stem 28 that projects through the outer end of the valve casing and carries a handle 29. This handle is provided with an index pointer 30 cooperating with indicating marks 31 on the front face of the valve 65 casing. A coiled spring 32, surrounding the stem 28, bears against the head 27 and the inner end of the valve chamber to hold the valve against accidental turning movement. The head 27 is provided with a channel or passageway 33, providing a pair of opposite stop walls 34. The ends of the passageway 33 are flared, and each is of sufficient extent to simultaneously uncover two of the adjacent ports in the nipples 15—18. 70 The stops 34 are each of sufficient extent to cover one of these ports and being oppositely disposed, will obviously simultaneously cover two opposite ports.

Assuming the fan in operation, if the 80 valve is moved to "open" position, its relation will be as shown in Figure 6, so that air delivered through the nipple 15 into the casing can flow freely through all three ports 16, 17 and 18, and thus deliver blasts through 85 the various nozzles 10, 12 and 13. Under some conditions, it is desirable to cut down the air delivered through the side nozzles 12 and 13 or cut it off entirely. This obviously can be easily accomplished by turning the valve until the stops 34 are more or less across the ports, through the nipples 17 and 18. The supply of air to all three 90 of the nozzles can also be cut down by moving one of the ports across the intake 95 nipple 15, and this supply can be completely cut off if desired by closing said intake nipple.

From the foregoing, it is thought that the construction, operation and many advantages of the herein described invention 100 will be apparent to those skilled in the art, without further description, and it will be understood that various changes in the size, shape, proportion and minor details of 105 construction, may be resorted to without

departing from the spirit or sacrificing any of the advantages of the invention.

Having thus fully described my invention, what I claim as new, and desire to 5 secure by Letters Patent, is:—

1. In paper feeding apparatus, the combination with a paper support, of nozzles for delivering loosening air blasts to different portions of the sheets placed on the 10 support, and means for relatively varying the amount of air delivered through the different nozzles while maintaining the nozzles in relatively fixed positions.

2. In paper feeding apparatus, the combination with a paper support, of nozzles for delivering loosening air blasts to different portions of the sheets placed on the support, a main air conduit, branches leading therefrom to the different nozzles, and 20 means for controlling the passage of air through the different branches to relatively vary the blasts of air delivered from the nozzles.

3. In paper feeding apparatus, the combination with a paper support, of nozzles for delivering loosening air blasts to different portions of the sheets placed on the support, a valve casing having an inlet and a plurality of outlets, a supply conduit 30 leading to the inlet of the valve casing, a plurality of branch conduits leading from the casing to the different nozzles, and a valve in the casing for controlling the supply to the branch conduits to vary the 35 amounts of air delivered therethrough.

4. In paper feeding apparatus, the combination with a rear nozzle and side nozzles

for delivering blasts of air to different portions of the sheets placed on the support, a valve casing having an inlet and a plurality of outlet ports, a supply conduit connected to the inlet port, a plurality of branch pipes leading from the outlet ports to the nozzles, and a rotary valve in the casing having stops that are movable across the 40 ports to vary the amount of air passing therethrough.

5. In paper feeding apparatus, the combination with a rear nozzle and side nozzles for delivering blasts of air to different 50 portions of the sheets placed on the support, a valve casing having an inlet and a plurality of outlet ports, a supply conduit connected to the inlet port, a plurality of branch pipes leading from the outlet ports to the nozzles, a rotary valve having a passageway 55 therethrough, and spaced stops movable simultaneously across certain of the ports, and means for indicating the location of the stops.

6. In paper feeding apparatus, the combination with a paper support, of a plurality of nozzles for delivering loosening air blasts to different portions of the sheets placed on the support, means for supplying air to the respective nozzles, and means in the air supply means for relatively varying the amount of air supplied to said nozzles.

In testimony whereof, I affix my signature in the presence of two witnesses.

ALBERT BROADMEYER
